UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

FLUID-ACTUATED INLET VALVE FOR ROCK DRILLS.

Application filed December 6, 1921. Serial No. 520,844.

To all whom it may concern:

Be it known that I, FRED M. SLATER, a citizen of the United States, and a resident of Easton, county of Northampton, and State of Pennsylvania, have invented a certain Fluid-Actuated Inlet Valve for Rock Drills, of which the following is a specification, accompanied by drawings.

This invention relates to fluid actuated rock drills, but more particularly to a fluid actuated valve controlling only the inlet supply, the exhaust being controlled by the piston.

Inlet valves of the usual type have been subject to the following defects: Either the piston has been long and consisted of two heads and a joining neck, or else it has been necessary to throw the valve by compression.

The objects of the invention are to enable the valve to be thrown by live air and utilize a piston having one head, thus decreasing the over-all length of the piston and weight of the machine.

Further objects of the invention will hereinafter appear, and to all of these ends the invention is shown in the accompanying drawings, in which—

Figure 1 is a diagrammatic view in longitudinal sectional elevation, of so much of a rock drill as will serve to illustrate the invention, with the piston at the beginning of its forward stroke.

Figure 2 is a similar view with the piston at the beginning of its rearward stroke.

Figures 3 and 4 are similar views of a modification of the valve.

Referring to the drawings, and at first more particularly to Figures 1 and 2, the cylinder A of the rock drill is provided with the piston B, having the head C and forward extension or shank D. The fluid actuated valve E, in accordance with this invention, controls the inlet supply F and free exhaust ports G, of which there may be one or more, in this instance two being indicated, are controlled by the piston head C.

The inlet valve E is provided with the end heads H and a single central flange J of larger diameter than the heads H. The central flange J controls the passage of mo-

tive fluid from the inlet F to both ends of the cylinder A, through the passages K and L.

Small ports, in this instance indicated as the ports O and P connect the inlet F directly with the spaces Q and R respectively, at the ends of the valve, and connecting passages S and T join the spaces Q and R at each end of the valve with the cylinder at points between the middle and the ends of the cylinder.

The valve may be mounted in a valve chest, if desired, in any suitable manner, and in this instance, the ends of the valve chest are shown closed by the valve chest bushings U and V, as a convenient construction. The small ports O and P are shown in all the figures, as extending through the valve itself as a preferable construction, and in Figures 1 and 2 they may conveniently be formed in the central valve flange J. These small ports O and P are cut off by the operation of the valve, and alternately connect the inlet F directly with the spaces Q and R at the ends of the valve as a preferable construction.

The valve is thrown by live motive fluid passing to the ends of the valve, through the small ports O and P and building up pressure at one of said ends of the valve, when the piston closes one of the connecting passages K or L, the other of said connecting passages being opened to atmosphere through the cylinder. The valve is held by the pressure of live motive fluid on one face of the central flange J, which as stated, is of larger diameter than either head of the valve.

In the operation of the device, let it be assumed, that the piston B in Figure 1, is starting on its forward stroke. The valve is in the position indicated in said figure, and live motive fluid passes from the inlet supply F around the valve, through the supply passage K behind the piston head C, driving the piston forward. The pressure of motive fluid on the face of the central flange J holds the valve in the position indicated. Any leakage from the inlet, past the rearward head H of the valve, only serves to hold the valve in the desired position. Motive fluid passing through the

small port O to the other end of the valve, leaks to atmosphere through the open exhaust G.

As the piston moves forward, and un-
5 covers the exhaust G, the pressure holding
the valve in its forward position is reduced
to atmosphere, both behind the central valve
flange and behind the rearward valve head H.
10 The exhaust from the forward end of
the cylinder having been closed by the pi-
son in its forward movement, and the piston
having over-run the connecting passage S,
the pressure of the live motive fluid building
15 up in front of the forward valve head H,
throws the valve rearwardly, opening the
supply of motive fluid to the forward end
of the cylinder, which starts the piston rear-
wardly and at the same time, the pressure
20 on the forward face of the central flange J
holds the valve in rearward position.

When the valve is in the position indicated
in Figure 1, it will be observed that the
small port P is cut off from the inlet supply
and similarly in the position indicated in
25 Figure 2, the small port O is cut off from the
inlet supply. This is the preferable con-
struction, because if these small ports O
and P were continuously open to the inlet
supply, there would be a certain amount of
30 waste motive fluid passed through the said
ports to atmosphere, through the open ex-
haust port, and the motive fluid would not
be alternately admitted to either end of the
valve, although the valve would operate in
35 substantially the same manner.

In the modification shown in Figures 3
and 4 the valve is provided with the small
ports O' and P' conveniently located at an
angle in the body of the valve at the base
40 of the central flange J' instead of extending
from the circumference of the flange to the
body of the valve, as in Figures 1 and 2.
Otherwise the construction of the modifi-
cation is like that indicated in the other figures
45 and the operation of the device is similar.
When the valve is in the position indicated
in Figure 3, the live motive fluid may pass
freely through the small port O' to at-
mosphere through the open exhaust, but the
50 small port P' is cut off and motive fluid does
not pass through said port owing to the
fact that the connecting passage T is closed
by the piston head C. Similarly in Figure
55 4, the small port P' is open for the passage
of motive fluid and the other small port O'
is cut off, so that as in Figures 1 and 2,
motive fluid is alternately admitted through
said small ports to opposite ends of the
60 valve, for throwing said valve in opposite
directions.

I claim:

1. In a fluid actuated rock drill, the com-
bination with the cylinder and reciprocating
piston, of a fluid actuated valve controlling
the inlet supply and having end heads and

a single central flange of larger diameter
than the heads, the central flange controlling
the passage of motive fluid from the inlet
to both ends of the cylinder, small ports
70 connecting the inlet directly with the spaces
at the ends of the valve, connecting passages
joining the spaces at each end of the valve
with the cylinder at points between the middle
and the ends of the cylinder, and a free
75 exhaust port controlled by the piston, where-
by the valve is thrown by the live motive
fluid passing to the ends of the valve
through said small ports and building up
pressure at one of said ends of the valve
80 when the piston closes one of said connec-
tion passages, the other of said connecting
passages being open to atmosphere through
the cylinder, and the valve being held by
the pressure of live motive fluid on one face
85 of the central flange of larger diameter than
the heads of the valve.

2. In a fluid actuated rock drill, the com-
bination with the cylinder and reciprocating
piston, of a fluid actuated valve controlling
the inlet supply and having end heads and
a single central flange of larger diameter
90 than the heads, the central flange controlling
the passage of motive fluid from the inlet
to both ends of the cylinder, small ports to
alternately connect the inlet directly with
the spaces at the ends of the valve, connect-
95 ing passages joining the spaces at each end
of the valve with the cylinder at points
between the middle and the ends of the cyl-
inder, and a free exhaust port controlled by
the piston, whereby the valve is thrown by
100 the live motive fluid passing to the ends of
the valve through said small ports and
building up pressure at one of said ends of
the valve, when the piston closes one of said
connecting passages, the other of said connec-
105 connecting passages being open to atmosphere
through the cylinder, and the valve being
held by the pressure of live motive fluid
on one face of the central flange of larger
diameter than the heads of the valve.

3. In a fluid actuated rock drill, the com-
bination with the cylinder and reciprocating
piston of a fluid actuated valve controlling
the inlet supply and having end heads and
a single central flange of larger diameter
115 than the heads, the central flange controlling
the passage of motive fluid from the inlet to
both ends of the cylinder, small ports extend-
ing through the valve and connecting the in-
let directly with the spaces at the ends of the
120 valve, connecting passages joining the spaces
at each end of the valve with the cylinder
at points between the middle and the ends
of the cylinder, and a free exhaust port con-
trolled by the piston, whereby the valve is
125 thrown by the live motive fluid passing to
the ends of the valve through said small
ports and building up pressure at one of
said ends of the valve when the piston closes

one of said connecting passages, the other of said connecting passages being held open to atmosphere through the cylinder, and the valve being held by the pressure of live motive fluid on one face of the central flange of larger diameter than the heads of the valve.

4. In a fluid actuated rock drill, the combination with the cylinder and reciprocating piston of a fluid actuated valve controlling the inlet supply and having end heads and a single central flange of larger diameter than the heads, the central flange controlling the passage of motive fluid from the inlet to both ends of the cylinder, small ports extending through the valve to alternately connect the inlet directly with the spaces at the ends of the valve, connecting passages joining the spaces at each end of the valve with the cylinder at points between the middle and the ends of the cylinder, and a free exhaust port controlled by the piston, whereby the valve is thrown by the live motive fluid passing to the ends of the valve through said small ports and building up pressure at one of said ends of the valve when the piston closes one of said connecting passages, the other of said connecting passages being open to atmosphere through the cylinder, and the valve being held by the pressure of live motive fluid on one face of the central flange of larger diameter than the heads of the valve.

5. In a fluid actuated rock drill, the combination with the cylinder and reciprocating piston of a fluid actuated valve controlling the inlet supply and having end heads and a single central flange of larger diameter than the heads, the central flange controlling the passage of motive fluid from the inlet to both ends of the cylinder, small ports extending through the central flange and connecting the inlet directly with the spaces at the ends of the valve, connecting passages joining the spaces at each end of the valve with the cylinder at points between the middle and the ends of the cylinder, and a free exhaust port controlled by the piston, whereby the valve is thrown by the live motive fluid passing to the ends of the valve through said small ports and building up pressure at one of said ends of the valve when the piston closes one of said connecting passages, the other of said connecting passages being open to atmosphere through the cylinder, and the valve being held by the pressure of live motive fluid on one face of the central

flange of larger diameter than the heads of the valve.

6. In a fluid actuated rock drill, the combination with the cylinder and reciprocating piston of a fluid actuated valve controlling the inlet supply and having end heads and a single central flange of larger diameter than the heads, the central flange controlling the passage of motive fluid from the inlet to both ends of the cylinder, small ports, extending through the central flange, to alternately connect the inlet directly with the spaces at the ends of the valve, connecting passages joining the spaces at each end of the valve with the cylinder at points between the middle and the ends of the cylinder, and a free exhaust port controlled by the piston, whereby the valve is thrown by the live motive fluid passing to the ends of the valve through the said small ports and building up pressure at one of said ends of the valve when the piston closes one of said connecting passages, the other of said connecting passages being open to atmosphere through the cylinder, and the valve being held by the pressure of live motive fluid on one face of the central flange of larger diameter than the heads of the valve.

7. In a fluid actuated rock drill, the combination with the cylinder and reciprocating piston of a fluid actuated valve controlling the inlet supply and having end heads and a single central flange of larger diameter than the heads, the central flange controlling the passage of motive fluid from the inlet to both ends of the cylinder, small ports connecting the inlet directly with the spaces at the ends of the valve, connecting passages joining the spaces at each end of the valve with the cylinder at points between the middle and corresponding ends of the cylinder, and a free exhaust port controlled by the piston, whereby the valve is thrown by the live motive fluid passing to the ends of the valve through said small ports and building up pressure at one of said ends of the valve when the piston closes one of said connecting passages, the other of said connecting passages being open to atmosphere through the cylinder, and the valve being held by the pressure of live motive fluid on one face of the central flange of larger diameter than the heads of the valve.

In testimony whereof I have signed this specification.

FRED M. SLATER.
